HENRY D. JAMES, OF EDGEWOOD, PENNSYLVANIA, ASSIGNOR TO WESTINGHOUSE ELECTRIC & MANUFACTURING COMPANY, A CORPORATION OF PENNSYLVANIA

SAFETY OPERATION BY BUFFER

Application filed April 18, 1930. Serial No. 445,319.

My invention pertains to a safety device for checking the speed of an elevator car and more specifically to a combination safety-buffer in which the engagement of the buffer by the car causes the application of a safety-breaking device carried by the car to aid the buffer in checking the car speed.

It is common, in elevator practice, to provide a buffer in the pit at the bottom of the elevator shaft to gradually absorb the kinetic energy of the moving car and bring it to a relatively smooth stop in the event that the car should travel beyond its normal limits.

In the initial engagement of the car with the buffer, however, the impact is considerable, because it is necessary to overcome the inertia of the moving part of the buffer and impart to it a velocity equal to the velocity of the car. The shock of the impact sets up vibrations in the car which are detrimental to the equipment and cause discomfort to the passengers. Furthermore, buffers suitable for checking the speed of modern high-speed elevators are difficult to design and install.

It is, accordingly, an object of my invention to provide a buffer-safety combination which will eliminate the difficulties and disadvantages attending the conventional buffer installations.

It is an object of my invention to provide means carried by an elevator car for engaging the buffer to gradually absorb the inertia of the moving portion of the buffer.

It is also an object of my invention to provide a braking device and a buffer-engaging means carried by the car to gradually absorb the inertia of the moving portion of the buffer and simultaneously apply the braking device.

It is a further object of my invention to provide a braking device carried by the elevator car which will be automatically applied by the engagement of the car and the buffer with a force commensurate with the velocity and loading of the car.

In accordance with my invention, the plunger of the buffer is provided with a head of wedge-shape, and the car is provided with a pair of jaws having angularly

disposed surfaces suitable for engagement with the head of the buffer. A braking device is carried by the car and is associated with the wedge-engaging jaws so that, as the head enters between the jaws and forces them apart, the braking device is applied.

Other objects of my invention will become evident from the following detailed description, taken in conjunction with the accompanying drawings, in which

Fig. 1 is a view partially in side elevation and partially in section, showing an elevator car and a buffer arranged in accordance with my invention.

Fig. 2 is a sectional side view of the car safety-braking device, taken on the section lines II—II of Fig. 3, and

Fig. 3 is a sectional plan view of the car safety-braking device taken on section lines III—III of Fig. 2.

Referring to the drawings, the apparatus shown in Fig. 1 comprises an elevator car C operating between guide rails 1 and 2 in the usual manner. The hoist equipment and control apparatus has been omitted since it may comprise any conventional elevator installation and would complicate the disclosure if shown.

As shown in Fig. 1, the plunger 3 of a buffer B is provided with a head 4 of wedge-shape which enters between a pair of engaging jaws 5 and 6 carried by the car. Means is provided within the buffer to prevent rotation of the piston and maintain the head 4 in its proper relative position. It will be apparent that the entrance of the head will force apart the jaws 5 and 6 and their associated shafts 7 and 8. The motion of the shafts 7 and 8, when forced apart by the entrance of the head 4, causes the application of the car safety device to grip the rails, in a manner more fully set forth with reference to Figs. 2 and 3.

If the car engages the buffer at a very high velocity, the buffer head 4 will be forced through between the jaws 5 and 6 and will engage the impact plate 14 carried by the car. Engagement with the plate 14 will cause the movable portion of the buffer to travel with a velocity equal to that of the car, but, before

this occurs, it will have been accelerated to a velocity comparable with that of the car because of the sliding engagement with the jaws 5 and 6, and the impact will be slight, if it occurs at all.

The safety device carried by the car is shown in greater detail in Figs. 2 and 3. Shafts 7 and 8 are supported in cross pieces 21, 22, 23 and 24 through which they extend. The inner extremities of shafts 7 and 8 carry jaws 5 and 6, respectively, for receiving the head 4 of the buffer plunger, as previously set forth. To prevent rotation of the jaws 5 and 6, a guide 32 is provided. The outer extremities of the shafts carry wedge members 34 which are supported with their apices directed outwardly. The apex of each wedge is received between a pair of rollers 36 and 37, shown more clearly in Fig. 3, and the rollers are journaled in the ends of levers 38 and 39 mounted upon the pivot members 41. The outer extremities of levers 38 and 39 are provided with suitable braking surfaces 43 and 44 for engaging the guide rails 1 and 2 to stop the car.

The movable parts of the braking device carried by the car constitute a brake actuator which diverts a portion of the force of engagement of the car on the buffer to apply the brake.

Springs 48 and 49 are provided to normally hold the roller-supporting ends of the levers 38 and 39 together and the braking ends of the levers apart and disengaged from the rail. Springs 33 are provided to retrieve the shafts 7 and 8 to their inoperative positions.

My invention is more readily described, however, when considered in connection with an assumed operation thereof.

Assuming that the car descends and strikes the buffer, and the head 4 enters between the jaws 5 and 6, the entrance of the head 4 between the jaws 5 and 6 will force them apart, and they will, in turn, force the shafts 5 and 6 outwardly, thereby forcing the wedges 34 between the two pairs of rollers 36 and 37. When the rollers 36 and 37 are forced apart, the levers 38 and 39 will be rocked about their pivots 41, in a manner similar to a pair of scissors, thereby urging the braking surfaces 43 and 44 together to squeeze the webs of the guide rails and check the speed of the car.

It will be apparent that the impact of the car striking the buffer will be very slight since it is absorbed gradually by the sliding engagement of the head with the jaws and the springs 33.

The force with which the car safety-braking device is applied will be commensurate with the force of engagement of the car with the buffer which is proportional to the velocity of the car and the load carried thereby. In addition to the braking effort applied by the car-braking device, the buffer will also be

simultaneously effective to check the speed of the car in the usual manner.

I do not wish to be restricted to the specific structural details, or arrangement of parts set forth, as various modifications may be effected without departing from the spirit and scope of my invention. I desire therefore, that only such limitations shall be imposed as are necessitated by the prior art and the spirit of the appended claims.

I claim as my invention:

1. In combination, an elevator car, a braking device carried thereby, a buffer mounted on the bottom of the hatchway for engaging the car to reduce its speed when it overruns a terminal, and brake-actuating means carried by the car for diverting a portion of the force of engagement of the car with the buffer to apply said braking device, with a force proportional to the velocity and loading of the car.

2. The combination with an elevator car operating between guide rails, and a buffer mounted on the bottom of the hatchway between said rails and below the normal lower limit of travel of said car, of a braking device carried by the car comprising rail-gripping members and actuating means therefor engageable by the buffer to actuate the braking device, and absorb the inertia impact energy.

3. In combination with an elevator car, a buffer mounted in the path of movement of said car below the normal lower limit of travel thereof, a head of wedge shape on the plunger of said buffer, a braking device carried by the car, and actuating means for applying said braking device to stop the car comprising cooperating surfaces operative to receive said buffer head therebetween to divert a portion of the force of engagement of the car with the buffer for the purpose of applying the braking device, and absorbing the inertia impact energy.

4. In combination, an elevator car movable vertically in a shaft, a buffer mounted on the bottom of said shaft for engagement with the car, a head of wedge shape carried by the plunger of said buffer, a braking device carried by the car comprising means for gripping the rails to stop the car, and actuating means for applying said braking device comprising cooperative flat surfaces operative to receive said buffer head therebetween, and means for transmitting the force so diverted to move the said gripping means into operative engagement with the rails, when the car engages the buffer.

In testimony whereof, I have hereunto subscribed my name this 11th day of April, 1930.

HENRY D. JAMES.
